SYRINGE

Paul S. Madsen, Bethany, Conn., assignor to The
Seamless Rubber Company, New Haven, Conn.,
a corporation of Connecticut

Application July 15, 1949, Serial No. 104,905

15 Claims. (Cl. 128—232)

1

This invention relates to syringes, and more particularly to vaginal syringes of the kind described in the Gow and Manville application, Serial No. 754,514, filed June 13, 1947, in which the article comprises a compressible bulb, a douche pipe, the douche pipe being reversible from its operative position so as to take a position in which it extends inwardly into the bulb. In this latter position the open butt end of the douche pipe is covered over by a closing cap, and it is possible to carry about the syringe when the bulb is full of liquid.

One of the objects of the present invention is to provide an improved syringe of this type.

Another object is to improve the structure adjacent the connection of the pipe with the discharge portion of the bulb, with a view to increasing the protection against leakage of liquid from the bulb interior.

Another object is to provide a syringe of this type with means for preventing spouting or "geysering" of liquid from the pipe with the bulb contains a quantity of liquid and the pipe is in the inwardly projecting position, at the time the closing cap is being removed.

In the accompanying drawing:

Fig. 1 is a side elevation of a syringe embodying the invention, showing the same as ready for transportation;

Fig. 2 is an end view of the article shown in Fig. 1;

Fig. 3 is an enlarged section on line 3—3 of Fig. 2; and

Fig. 4 is a detail view showing a part of the discharge portion of the bulb as it appears when the douche pipe is removed.

In the drawing, the syringe structure in general is similar to that disclosed in the previously mentioned Gow and Manville application, the bulb, the douche pipe, and the cap being of the same kind. The present improvements relate especially to the structure employed at the discharge portion of the bulb for insuring against leakage of liquid from the bulb when the pipe is in the operative position and in the stored-away position, and to a structure or formation of the bulb bottom which cooperates with the pipe when the latter is in the stored position, as hereinafter described. The douche pipe carries intermediate of its ends an enlarged portion, generally cylindrical in shape, that is provided with screw threads so that the pipe can be screwed into a liner or bushing mounted in the discharge end of the bulb, and at the butt end of the pipe screw threads are provided for the attachment of the closing cap.

In the drawings, the body of the syringe is generally indicated at 10, the same comprising a bulb portion 11 and a shield portion 12. The discharge portion of the bulb is indicated at 13, the liner or bushing at 14, and the douche pipe at 15.

2

15. The threaded enlargement on the douche pipe which screws into the liner 14 is indicated at 16, the screw threads on the butt end portion of the douche pipe are indicated at 17, and the closing cap at 18. The douche pipe is similar to that disclosed in the Gow and Manville application, the same being provided with an interior bore 19 and having a bulbous end portion 20 provided with a central opening 21 in the tip, this opening being supplied with liquid squirted out through small perforations in an internal extension 22 within the bulbous portion and in communication with the bore 19.

The discharge portion 13 of the bulb is in the form of a bore or passage having such contour that the liner is received therein to provide the structure shown in Fig. 4. The liner is made of sheet metal or other suitable material, and preferably has a thin wall, and the same is placed in position relatively to the bulb by molding the rubber of the bulb about the liner. In the wall of the liner, intermediate of its ends, a screw thread 23 is directly formed or pressed, adapted to be engaged by the screw-threaded enlargement 16 of the pipe. Referring to Fig. 4, the upper end of the sheet metal liner is provided with an outwardly and downwardly bent anchoring flange 24 embedded for anchoring purposes in the wall of the shield portion 12. Above the liner (Fig. 4) the discharge portion of the bulb has an open part 25 formed in the rubber, which is substantially aligned with the inner surface of the liner. At the lower end of the liner (Fig. 4) the same is formed or bent to provide a portion 26 which is turned or curled in a radially inward direction for purposes of anchoring, and this curled end of the liner is embedded in a rubber wall portion presenting a hole or opening 27 that is of substantially less diameter than the internal diameter of the liner body. In other words, the rubber wall is thickened in this region so as to embed the curled portion 26 and so as to provide in the rubber an opening 27 of decreased diameter. At the upper end (Fig. 4) of this portion of reduced diameter, 45 and adjacent the lower border of the threaded portion of the liner, a sloping surface 28 is formed on the rubber so as to provide an upwardly and radially outwardly sloping seat against which the threaded enlargement of the douche pipe is adapted to engage for the purpose of providing a sealing valve. This valve is formed in part by the rubber surface on seat 28, and in part by the sloping shoulder on the pipe. The pipe has two of these sloping shoulders, one of which, indicated at 29, is at one end of the part 16 and acts to shut off liquid when the pipe is in the position shown in Fig. 3, and the other of which, indicated at 30, acts when the pipe is in the outwardly extended position.

It will be apparent that, by the described con-

struction, it will be impossible for liquid contained in the bulb to have access to any open space externally disposed with reference to the liner. It will also be apparent that it will be impossible for liquid which reaches the opening 21 from having egress from the bulb if the douche pipe is firmly seated against the seat 23 in either of the described positions of the pipe. It will also be apparent that, by the described construction, the liner is very effectively anchored in the rubber of the bulb so that, even under hard usage, it cannot become displaced or work out of position. Dislocation of the liner is prevented by the curled portion 26, which prevents the liner from moving either longitudinally or laterally, and this part also serves as an inner reinforce for the part of the bulb provided with the inclined seat. The flange 24 at the other end of the liner also serves to prevent dislocation of the liner either longitudinally or laterally.

It will be noted that the rubber against which the enlargement of the douche pipe seats is integral with the rubber in the bulb wall, and that the rubber in the bulb wall is so located as to prevent liquid from passing into a space around the liner, and it will be noted further that the liner at its inner end is continued into a rubber shoulder provided at the juncture of the filler bore or cavity with the main cavity of the bulb.

Supposing that the syringe is in the condition shown in Fig. 3, and that it is carrying a body of liquid, the syringe will be ready for instant use upon removing the closing cap 18 and reversing the position of the pipe. In such case the bulb is usually held in one hand while the other hand is used to unscrew the cap. Owing to the fact that the holding hand usually exerts some compressive action upon the bulb under these circumstances, there is a tendency for liquid to be squirted out of the butt end of the pipe as soon as the cap is released sufficiently to open the bore which it normally closes. In order to prevent spouting or "geysering" of the syringe under these conditions, the present construction involves means in association with the bottom of the bulb which prevents entrance of liquid into the lower end of the pipe, or substantially impedes the entrance of liquid into the pipe, by way of the hole 21, when the pipe has been screwed into the position of Fig. 3. For this purpose the bottom 31 of the bulb is provided with an upward projection 32 the upper surface of which is recessed, as shown at 33, and shaped to present a shallow concavity and to engage the pipe nozzle in the region around the hole 21 when the pipe is in the stored position. Thus, when the person holding the syringe in one hand exerts lateral pressure upon the bulb at the time the cap is being released, liquid cannot be forced into the lower end of the pipe, or at any rate cannot be forced into it in any substantial degree. Therefore, when the upper end of the pipe bore is opened or uncovered, there will be no spouting of liquid from the syringe. The sealing means herein shown, comprising the resilient rubber portion of the bulb, making contact with the nozzle in the region around the nozzle opening, acts to seal off the pipe sufficiently to prevent spouting.

It will be understood that in manufacturing the syringe, the liner of the discharge portion will be suitably positioned in a mold containing uncured rubber which is molded to form a shouldered portion embedding the lower end portion of the liner, and another portion embedding the flange at the upper end of the liner, the rubber containing suitable curing ingredients, and the rubber being

cured or vulcanized in any well-known manner. The term "rubber" is used in a broad and general sense.

The construction herein described is simple and relatively inexpensive, and for the stated reasons the improved syringe is more effective and convenient in operation than previously known devices.

Various changes can be made in the details without departing from the principles of the invention or the scope of the claims.

What I claim is:

1. In a syringe, an elastic bulb-like body having at one end a discharge portion, said discharge portion being in the form of a bore or passage forming a shoulder with the main cavity of the body, a bushing or liner mounted in said discharge portion and having its inner end embedded in said shoulder, said bushing being provided with a screw thread, and a douche pipe adapted to be screwed into said bushing and carrying valve means adapted to engage a valve seat provided upon said bulb body in a region adjacent said shoulder, said seat being located within the bushing at a point intermediate of the ends of the bushing.

2. In a syringe, an elastic bulb-like body having at one end a discharge portion, said discharge portion being in the form of a bore or passage forming a shoulder with the main cavity of the body, a bushing or liner mounted in said discharge portion and having its inner end embedded in said shoulder, said bushing being provided with a screw thread, and a douche pipe adapted to be screwed into said bushing and carrying valve means adapted to engage a valve seat provided upon said bulb body in a region adjacent said shoulder, said seat being located within the bushing at a point intermediate of the ends of the bushing, the inner end of the bushing having an inwardly turned portion embedded in the material of the body.

3. In a syringe, a bulb-like body of rubber having at one end a discharge portion, a sheet metal bushing mounted in said discharge portion placed in position intermediate of the ends of the discharge portion and having an outwardly turned end flange at the outer end and an inturned portion at the inner end, said flange and said inturned portion being embedded in the rubber, said body having on an integral portion thereof located within the bushing a valve seat, and a douche pipe carrying means adapted to engage said seat in a leak-proof manner.

4. In a syringe, an elastic bulb-like body having at one end a discharge portion, a reversible douche pipe adapted to be screwed into said discharge portion with the pipe in an inwardly extending position and having at its butt end portion provisions for mounting a closing cap covering the bore of the pipe, the distal end of said pipe being provided with an opening for the discharge of liquid, and means for closing said opening when the pipe is in the inwardly extending position, said means comprising an inwardly extending portion provided upon said bulb-like body.

5. In a syringe, an elastic bulb-like body having at one end a discharge portion, a reversible douche pipe adapted to be screwed into said discharge portion with the pipe in an inwardly extending position and having at its butt end portion provisions for mounting a closing cap covering the bore of the pipe, the distal end of said pipe being provided with an opening for the discharge of liquid, and means for closing said

opening when the pipe is in the inwardly extending position, said means comprising an inwardly extending portion provided upon said bulb-like body at the bottom of the body, said inwardly extending portion being adapted to make contact with the tip of the pipe around said opening.

6. In a syringe, an elastic bulb-like body having at one end a discharge portion, a reversible douche pipe adapted to be screwed into said discharge portion with the pipe in an inwardly extending position and having at its butt end portion provisions for mounting a closing cap covering the bore of the pipe, the distal end of said pipe being provided with an opening for the discharge of liquid, and means for closing said opening when the pipe is in the inwardly extending position, said means comprising an inwardly extending portion provided upon said bulb-like body at the bottom of the body, said inwardly extending portion being adapted to make contact with the tip of the pipe around said opening and presenting a shallow concavity in which the distal end of the pipe is received.

7. In a syringe, an elastic bulb-like body having a discharge portion, and a reversible hollow douche element adapted to be secured in said discharge portion with said element extending inwardly into the body and having at its butt end portion provisions for mounting a closing cap closing off the interior of the douche element, the distal end of the douche element being provided with a liquid-discharging opening and said distal end in the secured inwardly extending position of said element abutting the bulb-like body to close said opening.

8. In a syringe, an elastic bulb-like body having at one end a discharge portion, and a reversible douche pipe adapted to be screwed into said discharge portion with the pipe in an inwardly extending position and having at its butt end portion provisions for mounting a closing cap covering the bore of the pipe, the distal end of the pipe being provided with a liquid-discharging opening and said distal end in the fully screwed-in position of the pipe engaging the wall of said body in a manner to close said opening.

9. In a syringe, an elastic bulb-like body having at one end a discharge portion in the form of a bore or passage forming a shoulder with the main cavity of the body, said bore or passage having adjacent its inner end a portion of less diameter than the remainder of the bore or passage, said portion being presented by a radially inwardly extending integral part of the body wall, said portion having at its upper or forward part a shoulder presenting a valve seat and the bore or passage above or forwardly of said seat being provided with a screw thread, and a douche pipe provided with an enlarged portion externally screw threaded and adapted to engage said screw thread, said enlarged portion presenting at one end thereof a valve shoulder adapted to engage said valve seat for sealing said discharge portion.

10. In a syringe, an elastic bulb-like body having a discharge portion, a screw-threaded bushing mounted in said discharge portion, a seat integral with said body and located internally of said bushing adjacent its radially inner part, and a douche pipe adapted to be secured into said bushing with the pipe in an outwardly projecting position or to be screwed into the bushing with the pipe in an inwardly extending position, said douche pipe carrying shouldered valve means which in either of the stated positions

of said pipe makes contact with said seat to prevent leakage of liquid from the bulb.

11. In a syringe, an elastic bulb-like body having a discharge portion, a bushing having screw threads mounted in said discharge portion, a seat integral with said body and located internally of the bushing, and a douche pipe adapted to be screwed into said bushing, said douche pipe carrying valve means coacting with said seat.

10 12. In a syringe, an elastic bulb-like body having a discharge portion, a bushing mounted in said discharge portion having screw threads, a seat integral with said body and located internally of said bushing at the inner end thereof, and a douche pipe adapted to be screwed into said bushing, said douche pipe carrying valve means coacting with said seat and said bushing having adjacent its outer end an external flange by which it is embedded and anchored in the material of said bulb-like body.

15 13. In a syringe, an elastic bulb-like body having a discharge portion, a bushing mounted in said discharge portion having screw threads, an annular seat which is integral with said bulb-like body and located internally of said bushing, and a douche pipe adapted to be screwed into said bushing, said douche pipe carrying valve means coacting with said seat, and said bushing carrying at the respective ends anchoring members embedded in the material of said elastic body.

20 14. In a syringe, an elastic bulb-like body having a discharge portion, a bushing mounted in said discharge portion having screw threads, an annular seat which is integral with said bulb-like body and located internally of said bushing, and a douche pipe adapted to be screwed into said bushing, said douche pipe carrying valve means coacting with said seat, and said bushing carrying at the respective ends anchoring members embedded in the material of said elastic body, the anchoring member adjacent the outer end of said bushing being an outturned member integral with the bushing and the anchoring member adjacent the inner end of the bushing being an inturned member integral with the bushing.

25 15. In a syringe, an elastic bulb-like body having a screw-threaded discharge portion, an annular seat integral with said body and located internally and between the ends of said discharge portion, and a douche pipe adapted to be screwed into said discharge portion, said douche pipe carrying an annular shoulder adapted to make contact with said seat to prevent leakage of liquid from the bulb-like body.
